DESIGN FOR A CLOTHESPIN

Kent Cox, Far Hills, Ohio

Application April 18, 1949, Serial No. 2,103

Term of patent 14 years

(Cl. D17—6)

To all whom it may concern:

Be it known that I, Kent Cox, a citizen of the United States and resident of Far Hills, in the county of Montgomery and State of Ohio, have invented a new, original, and ornamental Design for a Clothespin, of which the following is a specification, reference being had to the accompanying drawing, forming part thereof, wherein:

Fig. 1 is a side elevational view of a clothespin, showing my new design;

Fig. 2 is an elevational view looking at the right side as shown in Fig. 1;

Fig. 3 is an elevational view looking at the back side as shown in Fig. 1; and

Fig. 4 is a plan view looking at the top side as shown in Fig. 2.

I claim:

The ornamental design for a clothespin, substantially as shown.

KENT COX.
